UNITED STATES PATENT OFFICE.

EDWARD MEAKIN PEARSON, OF WHEELING, WEST VIRGINIA.

DESIGN FOR A DISH.

SPECIFICATION forming part of Design No. 21,102, dated October 6, 1891.

Application filed September 14, 1891. Serial No. 405,700. Term of patent 3½ years.

To all whom it may concern:

Be it known that I, EDWARD MEAKIN PEARSON, a citizen of the United States, residing at Wheeling, in the county of Ohio and State 5 of West Virginia, have invented a new and useful Design for a Dish, of which the following is a specification.

The invention relates to a new and original design for dishes.

10 The object of the present invention is to provide an original, ornamental, and attractive design for dishes; and the leading feature consists of the general shape and ornamentation of the dish, the shape of the handles, and 15 the shape and disposition of the feet.

In the drawings, Figure 1 is a top plan view of a dish, showing the design. Fig. 2 is a side elevation. Fig. 3 is a reverse plan view.

Referring to the accompanying drawings, 1 20 designates a dish having a general diamond shape and comprising a diamond-shaped bottom 2 and outwardly-extending sides 3, arranged at an angle to each other. The dish is provided at its ends with curved U-shaped and ornamental handles 4 and at the corners 25 of its bottom with outwardly-extending feet 5. The cover 6 has a general diamond shape and is concavo-convex and is provided with a centrally-arranged sigmoidal handle 7, and its outer face is ornamented with scalloped edges 30 and with raised scallops 8. The sides 3 of the dish are also ornamented, as shown in the accompanying drawings.

The general appearance of the dish is neat, ornamental, and attractive. The centrally- 35 arranged handle of the cover and the handles of the dish have surface ornamentations.

What I claim is—

The design for a dish herein shown and described, substantially as set forth. 40

In testimony that I claim the foregoing as my own I have hereto affixed my signature in presence of two witnesses.

EDWARD MEAKIN PEARSON.
